REFLECTOR FOR AUTOMOBILES

George E. Howell, Windsor, Ontario, Canada, assignor
to Reflex Corporation of Canada Limited, Amherstburg,
Ontario, Canada, a corporation of Ontario, Canada

Filed Mar. 15, 1968, Ser. No. 10,994

Term of patent 14 years

U.S. Cl. D72—1
Int. Cl. D16—08

FIG. 1 is a front elevational view of a reflector for automobiles embodying my new design, the fragmentary automobile being shown in broken lines for illustrative purposes only.

FIG. 2 is a front elevational view of the reflector on an enlarged scale.

FIG. 3 is a bottom elevational view, the top elevational view being identical.

FIG. 4 is a fragmentary sectional view taken along the line 4—4 in FIG. 2.

FIG. 5 is a fragmentary sectional view taken along the line 5—5 in FIG. 2.

FIG. 6 is a fragmentary view in the direction of the arrows 6 in FIG. 4.

FIG. 7 is a fragmentary view in the direction of the arrows 7 in FIG. 4.

I claim:

The ornamental design for a reflector for automobiles, as shown and described.
